(No Model.)

C. A. TUCKER.

ANNUNCIATOR.

No. 350,449.

Patented Oct. 5, 1886.

UNITED STATES PATENT OFFICE.

CHARLES A. TUCKER, OF ISLIP, ASSIGNOR TO TUCKER & BAXTER, OF BROOKLYN, NEW YORK.

ANNUNCIATOR.

SPECIFICATION forming part of Letters Patent No. 350,449, dated October 5, 1866.

Application filed July 9, 1885. Serial No. 171,104. (No model.)

To all whom it may concern:

Be it known that I, CHARLES A. TUCKER, residing in the town of Islip, in the county of Suffolk and State of New York, have invented 5 certain new and useful Improvements in Annunciators and Drops therefor, of which the following is a full, clear, and exact description, which will enable others skilled in the art to which my invention appertains to make and 10 use the same, reference being had to the accompanying drawings, forming a part hereof, in which—

Figure 1 is a side view of a part constituting one member of the annunciator, showing 15 the drop raised. Fig. 2 is a similar view showing the drop down. Fig. 3 is a plan showing two members in position in the annunciator-case, the drops raised. Fig. 4 is a view of part of the side of the annunciator- 20 case, showing the arrangement of the handle for setting the drops. Fig. 5 is a back view of the supporting piece E. Fig. 6 shows the method of arranging the setting device when 25 the drops are disposed on three planes.

Similar letters of reference indicate like parts in all the drawings.

The object of my invention is to simplify and improve the construction and operation of that part of the annunciator called the 30 "drop" or "indicator," and it is applicable to all kinds of annunciators, but especially to those kinds in which electricity is employed.

A represents the annunciator-case, which is made of wood of suitable size to contain the 35 number of drops required, and in this case, on a suitable bar or back-iron, F, are mounted the members or drops. Each member or drop consists, essentially, of a metallic frame, B, composed of an upper and a lower arm, parallel 40 to each other, and a vertical part connecting them, conveniently made of one piece of metal bent or cast into the required shape, the vertical portion of which may be readily screwed or otherwise rigidly secured to the back iron, 45 F, as clearly shown in Figs. 1 and 2.

Between the upper and lower arm of the frame B is mounted a suitable magnet, D, which is provided in the usual manner with wires c and d, one of which runs to one pole 50 of a battery directly, and the other, through

a suitable gong or bell, to the other pole of the battery to form an electrical circuit.

To the lower arm of the frame B is pivoted a vertical armature-carrier, E, which consists of a small metal bar having its upper end 55 brought to a knife-edge, as shown in Fig. 5, and is pivoted near its lower end to the end of the lower bar of the frame B, and is adjusted and balanced so that in its normal condition it will hang slightly inclined away from 60 the magnet D, as shown in Fig. 1, its upper edge reaching out far enough to support in position the edge of the drop C, as also shown in Fig. 1. The drop C consists of a flat plate, which may be conveniently made of tin, and 65 at the middle of its upper edge is attached to a curved portion or arm, a, which is pivotally hung on the upper arm of the frame B, and so balanced that when free the drop C will fall by its own weight into the position shown in Fig. 70 2, which will expose its flat side to view, and indicate its appropriate call or signal, the front of the indicator being the side farthest from the magnet. It will be seen that by this construction and disposition of the parts the drop 75 C does not require to be weighted, as when it is balanced on or near its center, that the armature and its carrier may be made exceedingly small and light, and that the friction of withdrawing the drop support E from beneath 80 the drop is also exceedingly slight, so that a magnet and battery of very small power may be employed, and that the magnet, its support, and the drop mechanism may be made very light, compact, and cheap, that the operation 85 is very simple, and that there are no tension-springs of any kind to get out of order or require adjustment.

The operation is as follows: When all the drops in the annunciator are set, they will be 90 in the position shown in Figs. 1 and 3. When a signal is delivered to any particular drop, the circuit is closed, and the magnet of that drop is thereby excited, attracting the armature E, which withdraws the support from its 95 drop C and causes it to fall and to assume the position shown in Fig. 2. I prefer to have the upper bearing part of the supporting piece E finished to a knife-edge, as clearly shown in Fig. 5, as that makes the least friction in op- 100

eration. The best method of mounting these drops in the annunciator-case is to attach the frames B to the metal bar F, called the "back iron," to which they are suitably secured.

5 In arranging the members in a system, I make the following provision for resetting the drops: A metal rod, H, is fitted in bearings in each side of the case A and provided with a handle, G, on the outer side of the case for convenience. To this rod H are rigidly attached the spurs b b, which incline downward, as shown in Fig. 2, when not in use; but when employed to reset the drops the rod H is turned by means of the handle G until the 15 spurs b b, pushing against the pins k, raise the drops C. The lower edge of the drop pressing against the side of the support E moves it toward the magnet until the drop has passed above that support, when the supporting-piece 20 E falls outward again by its own weight, and the parts assume the position shown in Fig. 1. Then the handle G, moving back again, causes the spurs b b to assume the position shown in Fig. 2, while the drop retains the position 25 shown in Fig. 1. By this operation all the drops actuated by the spurs b b, whatever their number, are at once reset. In order that the rod H may be turned to just the right distance, I place stops g' g' on the side of the 30 case, which limit the scope of movement of the handle G.

In Fig. 6 is shown an arrangement of the rods H H on different planes when it is desired to dispose the drops in that manner.

35 The handle G is attached to one of the rods H, while all the rods H in the case are pivotally connected to the bar I, so that by turning the handle G all the rods H in the case will be at once operated, and any drops that have been 40 upset will be reset thereby.

For some purposes, especially for burglar-alarms, it is desirable that there should be means provided for continuing the alarm in the case where it has been sounded through 45 the circuit formed by means of the magnet D, should that circuit be again quickly broken. To accomplish this object I make an electrical connection which is independent of the magnets D by attaching a wire, i, to the rod H, 50 connecting it to one pole of the battery, and attaching a wire, j, to the back iron, F, which connects through the alarm-signal device with the other pole of the battery. When all the drops C are set, as shown in Fig. 1, there is 55 no electrical connection between the rod H and the back iron, F, as the pins K are insulated by means of suitable coverings, and the back irons, F, are attached to the wooden case A; but when one or more of the drops fall the 60 lower part of the metal arm b rests upon the metal rod H, as shown in Fig. 2, and the elec-

trical circuit is formed from the wires i j through the back iron, F, support B, rod H, and arm b, whereby the sounding of the alarm is continued until the fallen drop is reset, although the circuit operating the magnets D D should be broken. This arrangement and construction of the drops and their supports is exceedingly simple, no springs for adjusting the same are required, the parts are not liable to get out of order, and can be very strongly and cheaply made. 65 70

I do not claim, broadly, an annunciator-drop arranged to fall by gravity; but,

Having thus described my invention, what I 75 claim as new is—

1. An annunciator-drop consisting of the magnet D, frame B, drop C, having arm a, attached to its upper edge, and pivotally balanced to the upper arm of the frame B, in 80 combination with the armature-carrier E, pivotally balanced to the lower arm of the frame B in the path of the drop C, substantially as described and shown.

2. The annunciator-drop C, provided with 85 arm a, attached to the middle of its upper edge, and pivotally balanced to the arm of the frame B, in combination with a suitable support to uphold said drop at its free edge, such support pivotally balanced to the lower 90 arm of the frame B, and a suitable magnet to withdraw such support, substantially as described and shown.

3. An annunciator provided with drops C, supported by arms a, pivotally balanced to the 95 upper arm of the magnet-frame B, such arms having pins k, in combination with the rod H, carrying spurs b, adapted to engage with the pins k and reset the drops when upset by rotating the rod H, substantially as described 100 and shown.

4. An electrical annunciator provided with drops C, supported by arms a, pivotally balanced on the upper arms of the frames B, magnets D, with suitable battery-connections, 105 armature E', and armature-carrier E, pivotally balanced to the lower arm of the frame B in the path of the drops, and an electrical connection from the frames B to one pole of a battery, and an alarm-signal device interposed 110 in the circuit and adapted to be operated by closing the same, in combination with the rod H, connected to the other pole of the battery, and adapted to close the circuit and operate the alarm by contact with the arm a when one 115 of the drops is upset, substantially as described and shown.

CHARLES A. TUCKER.
